UNITED STATES PATENT OFFICE.

BENJAMIN F. COCKERELL, OF KANSAS CITY, MISSOURI.

PLASTER-BOARD CLIP.

1,286,233.

Specification of Letters Patent.

Patented Dec. 3, 1918.

Application filed September 4, 1917. Serial No. 189,499.

To all whom it may concern:

Be it known that I, BENJAMIN F. COCKERELL, a citizen of the United States, residing at Kansas City, Missouri, have invented 5 certain new and useful Improvements in Plaster-Board Clips, of which the following is a specification.

The subject-matter of this invention is a metal clip for securing plaster-boards and 10 the like to metal studding in the erection of partitions and other walls in buildings. The clip of my present invention belongs to the one-piece type which are cut and 15 pressed to shape from a single sheet-metal blank and are connected to the studding without the use of fastening wires or any other extraneous attaching means; and the principal objects of the invention are:

First, to provide a metal clip which may 20 be attached to a flanged stud through engagement with the flange only of the latter, and without embracing the complete stud, thereby effecting an economy of material 25 and also leaving the opposite edge of the stud unobstructed for the application thereto of the same or a different wall or covering as desired;

Second, to provide a metal clip having a 30 double channel for receiving both the upper edge of a lower plaster-board and the lower edge of an upper plaster-board;

Third, to provide a metal clip which can 35 be applied with equal facility and utility to either or both sides of the studding;

Fourth, to provide a metal clip which, when engaged with a stud, shall be held against rocking or tipping sidewise thereon and shall be securely locked to the stud 40 when the plaster-board is in place.

Fifth, to provide a metal clip of such a construction that by a slight adjustment of the dies or other forming tools it can be made to hold plaster-board of any thickness or to engage with any size of studding;

Sixth, to provide an improved metal clip, no portion of which has to be bent or changed in form or position when applying it to the studding.

Other objects and advantages secured by 50 the invention will be readily apparent to, and appreciated by, those skilled in the art

from the following detail description, taken in connection with the accompanying drawing forming a part of this specification and wherein—

Figure 1 is a horizontal section through a fragment of a partition wall employing my improved plaster-board clip, taken on the line 1—1 of Fig. 2;

Fig. 2 is a vertical section taken on the line 2—2 of Fig. 1;

Fig. 3 is a detail perspective view of the clip;

In the drawing 5 designates an element of the metal studding of the partition wall,—in this case a vertical channel-bar. These channels are commonly erected from one to three feet apart along the line of the partition and together from a skeleton support for a wall covering or filling that is applied 70 to either or both sides of the studding and commonly consists of rectangular plaster-boards 6 that are assembled edge to edge. For attaching the plaster-boards to the studding as well as properly alining the 75 meeting edges of the boards themselves, many different devices have heretofore been proposed and used. To expedite the work of erection and secure economies in material, time and labor, it is manifestly desirable to 80 make these plaster-board fastening devices as simple as possible consistently with efficiency and particularly to so construct them that they may be applied and locked to the studding without the use of extraneous fastening devices or bending or otherwise altering the shape or position of any part thereof. The improved fastening clip forming the subject-matter of my present invention possesses these and other advantageous 85 characteristics, and is shown in plan view in Fig. 1, in cross-section in Fig. 2, and in isometric detail in Fig. 3, from which it will be seen that the clip is formed from a single blank of sheet metal so cut and pressed to shape as to provide upper and lower channels for receiving the lower and upper edges respectively of two superposed plaster-boards, and on one side thereof means for securing it to the adjacent flange of the channel-bar stud 5. Describing the clip more specifically, 7 designates a horizontal

central web from one side of which extend marginal flanges 8 and 9 that form, with the web 7, one of the plaster-board receiving channels, and from the other side of which 5 extend in the opposite direction marginal flanges 10 and 11 that form, with the web 7, the other plaster-board receiving channel. The inner end portion of one of the flanges 8 is cut away from the web and bent outwardly in the form of a hook 12 that engages over the free edge and inner face of the adjacent flange of the channel-bar 5 in the manner clearly shown in Fig. 1. Opposite the free end of the hook 12 is a lug 13 10 that lies in the plane of the flange members 8 and co-operates with the hook to prevent sidewise turning or rocking of the clip on the stud 5. Between the non-turning lug 13 and the other flange member 8 is a laterally projecting locking prong 14 that cooperates with the hook 12 in holding the clip in proper relation to the stud.

The clip is applied to the channel stud 5 by first engaging the hook 12 over the free 25 edge of the flange of the stud while holding the clip in a canted or inclined position relatively to the plane of the studding, and then, by a combined swinging and endwise movement of the clip, bringing the automatic 30 locking prong 14 into position directly behind the rear face of the stud 5, which at the same time brings the main body of the clip into correct plaster-board receiving position. When in this position it will be 35 manifest that the hook 12 prevents the clip from moving outwardly away from the stud, the hook 12 and prong 14 prevent endwise shifting of the clip in either direction and also any substantial endwise tilting or rock- 40 ing, and the hook 12 and lug 13 prevent sidewise rocking or tilting, so that the clip is free for only a sliding up and down movement on the stud. It will further be noted that the clip may be applied with equal 45 facility to either side of the stud, the clip on one side being merely inverted relatively to its position on the other side, as clearly shown in Fig. 2.

In applying the plaster-boards to the studding, a row of clips on which the lower or depending flanges may be omitted if desired is first applied to the studs at the floor level. A horizontal row of plaster-boards is then laid with their lower edges 55 engaged with the clips. A second row of clips is then applied with their lower channels engaged with the upper edges of the plaster-boards. A second row of plaster-boards is then laid with their lower edges 60 seated in the upper channels of the second row of clips, and so on, until the partition wall is completed.

The manufacture of my improved clip involves only a few simple cutting and bend-

ing operations, and it is evident that by a 65 proper spacing of the flanges or side walls of the channels and of the hook 12 and prong 14 the clip may be made to fit any desired thickness of plaster-board or size of stud- 70

ing. It is believed that the foregoing description will suffice to make clear how the stated purposes and objects of the invention are attained. Manifestly minor changes in details may be made without essentially changing the described structure of the device or sacrificing any of the mechanical advantages secured thereby. Hence, I do not limit the invention to the exact structure shown and described except to the extent indicated in 80 specific claims.

I claim:

1. A one-piece clip for securing plaster-boards and the like to flanged studding, comprising a body member formed with a 85 channel to seat the edge of a plaster-board, a hook projecting laterally from a side wall of said channel and engaging over the free edge of the adjacent flange of the studding, and a locking prong projecting laterally 90 from said channel on the same side of the latter as said hook and engaging the studding at a point opposite the free end of said hook.

2. A one-piece clip for securing plaster-boards and the like to flanged studding, comprising a body member in the form of upwardly and downwardly facing channels having a common bottom wall or web, said channel adapted to seat the edges of plaster-boards, a hook projecting laterally from a 100 side wall of one of said channels and engaging over the free edge of the adjacent flange of the studding, and a locking prong projecting laterally from said body member on 105 the same side of the latter as said hook and engaging the studding at a point opposite the free end of said hook.

3. A one-piece clip for securing plaster-boards and the like to flanged studding, comprising a body member formed with a channel to seat the edge of a plaster-board, a lateral hook formed by an outwardly bent portion of a side wall of said channel engaging over the free edge of a flange of the 115 studding, a laterally projecting locking prong extending from an edge of the bottom wall of said channel and engaging the opposite side of the studding from said hook, and a vertical lug lying in the plane of said 120 side wall and engaging the opposite side of said flange from said hook and co-operating with the latter to prevent sidewise turning of the clip.

4. A one-piece clip for securing plaster-boards and the like to flanged studding, comprising a body member in the form of upwardly and downwardly facing channels

having a common bottom wall or web, said channels adapted to seat the edges of plasterboards, a lateral hook formed by an outwardly bent portion of a side wall of one of 5 said channels engaging over the free edge of a flange of the studding, a laterally projecting locking prong extending from an edge of said bottom wall and engaging the opposite side of the studding from said hook, and a vertical lug lying in the plane of said side 10 wall and engaging the opposite side of said flange from said hook.

BENJAMIN F. COCKERELL.
